UNITED STATES PATENT OFFICE

2,619,400

FURNITURE CONSTRUCTION

Charles Kramer, Jeffersonville, Ind.

Application April 1, 1948, Serial No. 18,445

2 Claims. (Cl. 312—345)

1

This invention relates to furniture in which a case, cabinet or the like is constructed with a compartment and a slidable drawer made of wood in which features are provided to maintain the drawer free from binding under long usage.

The main object of this invention consists of providing construction features that maintain the drawer in a free sliding relation to the case regardless of expansion or contraction or both of these inevitable forces that result from temperature changes and moisture content of the wooden members; summarily stated, to eliminate binding or sticking when pulled from the case.

Another object of this invention resides in adding an element to a normally constructed drawer, and a conventionally constructed case in which it is slidably mounted, that functions not only to prevent binding or sticking but to maintain the drawer substantially horizontal when withdrawn from the case.

This invention has as a further object a construction that reduces cost of production and eliminates much mental irritation during hot periods when humidity is excessive.

With reference to the accompanying drawings which disclose preferred embodiments of this invention:

Figure 1 is a side elevation of a portion of an open case with a slidable drawer mounted within a compartment therein.

Figure 2 is a section on an enlarged scale along line 2—2, Fig. 1 of the near side of the case and side wall of the drawer to show a vertical elevation of the metallic support body, referred to in the third paragraph above as "an element."

Figure 3 is a top fragmentary view of the upper surface of the side wall in which said metallic body is mounted.

Figure 4 is a section of Fig. 1 along line 4—4.

Figure 5 is an elevation of the metallic support body.

Figure 6 is a top view of Fig. 5.

Figure 7 is an elevation, partly in section, and a top view thereof to show another embodiment of this invention.

Figure 8 is an isometric projection, on a reduced scale, of the drawer, removed from the case, with the metallic support body shown in Figs. 1 through 6 removed and the modification shown in Fig. 7 included.

In the manufacture of case, cabinet and like furniture equipped with conventional sliding drawers the latter are usually credited with more than one half of the expense due largely to the necessity of employing highly skilled labor to fit

2

the drawers to the opening so as to slide freely and not sag when drawn from the case. To achieve this result in the hands of the user seems to have been impossible. This was particularly true not only for the user but for the manufacturer and merchant during August and September of 1947 when abnormal humidity was experienced, hence this improvement in furniture construction.

10 Numerals 10, 11, 12, 13 indicate respectively the vertical front, side and back walls of the drawer shown in Figs. 1 and 8. The front and back walls of the case in which the drawer is mounted is indicated respectively by numerals 14, 15.

15 The drawer, as found in standard practice, may be slidably mounted on a pair of spaced apart slide rails disposed directly beneath side walls 11 and 12. Slide rail 16 in Fig. 1 discloses the relation to side wall 12. The opposite side of the drawer and case are similarly constructed. Similarly related rub-rails are placed directly above the upper surfaces and aligned with the side walls. Numeral 16A designates the rub-rail aligned with side wall 12.

20 A wire or light rod, indicated generally by numeral 17, it bent at elbow 18 to provide shank 19, at elbow 20 to form shoe 21 and at elbow 22 to form depending arm 23. This is the element,

25 referred to above as "metallic support body." This element is securely and permanently mounted in groove 24, cut in each of the side walls, 11, 12, by means of inserting arm 23 in hole 25 and driving shank 19 securely in hole 26. While the upper surface of shoe 21 is shown in substantial contact with rub-rail 16A, obviously, this relation may be selected and predetermined by the location of hole 26 which is provided during fabrication of the side walls.

30 40 In the embodiment illustrated in Figs. 7 and 8, a modified support member 17A, preferably made of metal, is shown securely driven into the wood at the bottom of hole 13A (slightly larger in diameter than 17A to provide clearance) at the

45 lateral center of back wall 13 of the drawer. It should be noted that the shoe 17B projects above the side walls that can expand and contract, substantially the same as provided for the other structure, without materially affecting the originally established dimension between the top surface of the shoe and the bottom surface of the side wall that rests on the slide rail, thus contributing to the objects of the invention adverted to at the outset hereof and as presented in the

50 55 claims.

A separate case structure for the accommodation of a drawer equipped with the modified structure is not illustrated, however, it is believed obvious, that when support member 17A is located as shown in Fig. 8 a single longitudinally disposed rub-rail must be employed and located for contact by shoe 17B.

Since this invention has been developed to overcome long standing imperfections in furniture resulting from temperature changes and the inherent property of wood to absorb moisture and thereby distort the structure made thereof, it must be understood that the physical properties and disposition of the materials used over said imperfections are substantial factors for successfully practicing this invention, and that while the support member has been consistently referred to herein as being made of metal, certain other materials, such as plastics having a relatively low coefficient of expansion and high resistance to absorbing water can be employed without departing from the spirit of this invention.

While it will be apparent that the illustrated embodiments of my invention herein disclosed are well calculated to adequately fulfill the objects and advantages primarily stated, it is to be understood that the invention is susceptible to variation, modification and change within the spirit and scope of the subjoined claims.

What I claim is:

1. The combination of a cabinet or the like having a compartment provided with an opening in a side thereof and a rectangular wooden drawer lodged in said opening, slide rails spaced at the bottom of the compartment for engagement with the bottom faces of the side walls of the drawer, rub-rails aligned with the top faces of said side walls for assisting in retaining the

drawer horizontally when withdrawn from said compartment, and an elongated metallic support body freely disposed within a vertical groove formed in each of said side walls, each support

5 body having the lower end thereof secured to the bottom portion of said side wall and the top portion extending above the top face and within planes projecting from the vertical faces of the side member in which it is mounted for engagement with one of the rub-rails and attached adjacent the bottom edge of its respective side wall.

10 2. In a furniture construction, the combination of a drawer receiving frame and a drawer slidably mounted therein, said frame including a

15 pair of spaced apart drawer supporting slide rails, an upper rub-rail arranged above and longitudinally of the drawer, a support body formed with parallel arms, a long one and a short one joined together by a yoke, each of said arms

20 being freely disposed within recesses formed in one of the vertical members of the drawer, the bottom end of the long arm being secured to the bottom portion of the drawer and the yoke projecting upwardly above the upper edge surface

25 of said member and engaging said rub-rail to maintain the drawer in horizontal position when extended for access to the interior thereof.

CHARLES KRAMER.
